Patented Oct. 27, 1914.

UNITED STATES PATENT OFFICE.

GEORGE WILLIAM DAVIS, OF WESTMOUNT, QUEBEC, CANADA.

RIBBON MECHANISM FOR TYPE-WRITERS.

1,115,177.

Classification of Letters Patent.

Patented Oct. 27, 1914.

Application filed December 28, 1911. Serial No. 352,458.

To all whom it may concern:

Be it known that I, GEORGE WILLIAM DAVIS, residing at Westmount, in the Province of Quebec, Dominion of Canada, a subject of the King of Great Britain, have invented certain new and useful Improvements in Ribbon Mechanism for Type-Writers; and I do hereby declare that the following is a full, clear, and exact description thereof.

My invention relates to ribbon mechanisms of the class embodying a pair of members shifted by the ribbon when it nears the end of its travel in either direction and means adapted to operate through the medium of the ribbon shifted part and reverse the action of the feeding mechanism. Heretofore these members have been operatively connected together and consequently there has been considerable unnecessary strain exerted upon the ribbon due to its necessity to move both ribbon guides and the connection between them each time the ribbon feed was reversed.

The objects of the invention are to obviate the accidental reversal of the action of the ribbon feeding mechanism as might happen, for instance, when an operator inadvertently touches a part of the reversing mechanism; to render more positive, and, at the same time, more sensitive the actuating and retaining pawls and enable them to be automatically displaced when obstructing the positioning of the ribbon spools, to prevent inadvertent displacement of the friction devices for retarding the rotation of the ribbon spools; to reduce to a minimum the resistance offered to the ribbon by the instrumentality acted upon by it in the reversing action; and to provide ample clearance between the part shifted by the ribbon and the manually operated part for the purpose of insuring the placing of the former in proper position to be operated by the latter.

My invention consists of the construction, combination and particular arrangement of parts hereinafter described and pointed out in the claims.

For full comprehension, however, of my invention reference must be had to the accompanying drawings forming a part of this specification in which similar reference characters indicate the same parts, and wherein:

Figure 1 is a plan view of my improved ribbon feeding mechanism with sufficient

parts of a machine in which it is assembled to illustrate the application thereof; Fig. 2 is a transverse vertical sectional view of the unproved mechanism together with the parts of the machine to which it is directly connected for support, the section being taken on line A A Fig. 1; Fig. 3 is a side elevation partly in vertical sectional view of the ribbon spool and the actuating pawls therefor; Fig. 4 is a perspective view of one of the members for carrying my improved mechanism; Fig. 5 is a perspective view of one of the ribbon spool retaining pawls together with its carrying member; Fig. 6 is a perspective view of the ribbon guide illustrating its particular formation to operate the ribbon reversing mechanism; Fig. 7 is a perspective view of the rocking frame; Fig. 8 is a perspective view of the member effecting an operative connection between the dog rocker and ribbon reversing members; Fig. 9 is a perspective view of one of the ribbon reversing members; and Fig. 10 is a plan view of the ribbon spool tension device.

The mechanisms by which I obviate the inadvertent reversing of the ribbon feeding action, and, at the same time, reduce to a minimum the friction to be overcome by the ribbon, comprise a pair of independently operating mechanisms yieldingly retained in normal position and each including a part adapted when that mechanism is operated and held by the ribbon in a different position to register with and be shifted by a part operated by the writing mechanism, while the said individual mechanisms are independently connected to a displaceable unitary part for guiding the ribbon-spool-actuating pawls into operative relation with one or the other of the spools according to the particular individual mechanism operated by the ribbon. The preferred specific embodiment of this combination of mechanisms has as a carrier a flat horizontal bar 2 having a central lateral lug 3 by which it is pivotally carried in turn by the end of an arm 4 projecting toward the type-bar guide-plate 5 from a bracket 6 fastened to the underside of the quadrant 7 of the type-bar carrying frame. This bracket by its ends which are for the purpose downwardly bent and extended, as at 8, toward the type-bar guide-plate, affords fulcrum supports for a ribbon feed-pawl rocker-frame 9 to be presently further alluded to. The ends of this carrier

bar extend as at 19 at right angles to its main length and toward the plated and then diagonally outwardly through guideways formed by pairs of horizontal plates 12 and 13 fastened together and across arched portions 14 of the frame by screws 15, the lowermost plate of each pair being offset between its ends to form the guideways. The extreme ends of the bar are widened and formed with slots 16 extending parallel to the sides of the frame to afford a connection for pawl supporting members to be also presently further alluded to. This carrier has a pair of slides 20 mounted thereon and slidably connected thereto by headed pins 21 projecting through longitudinal slots 22 in the slides near each end thereof and fixed in the carrier, the adjacent ends of the slides having oppositely facing hooks 23 struck out of the plates from which the slides are formed and bent upwardly at right angles thereto. A retractile helical spring 24 connects the hooks together and the opposite ends of the slides have integral downwardly offset lateral dogs 25 projecting toward the platen. The edges of these slides having the dogs are also formed with a pair of standards 26 engaged by the forwardly forked arms 27 of a pair of ribbon guides 28. These forked ends are offset and disposed to, when under either normal feed or reversing conditions, lie substantially in the arcs described by the standards in the movement of the carrier when shifted, thus making the carrier free to move to either position without disturbing the ribbon guides or changing their position relatively to the ribbon. The middle portions 31 of these guides are formed to stand vertically and present perforated lugs 29 which with the arms 27 clasp the frame and in which and in perforations 30 in the arms are engaged the ends of pivot pins 96 loosely seated in the frame and suspended in position by enlargements 32 resting on the lugs. The ribbon guiding arms proper 28 extend diagonally rearwardly from the middle of the vertical portions 31, and contribute with the particular relative arrangement of the parts thereof to the equilibrium of these members and the transmission, with minimum resistance, of the movement of the ribbon end to the respective slide.

The dog-rocker bar 50 has mounted rigidly thereon a pair of upright arms 51 having a pair of forwardly projecting spaced fingers 52 in positions to clear the dogs 25 under normal ribbon-feeding conditions and on each writing action so operate as to intersect the plane in which the dogs are adapted to slide, but without engaging the dogs unless shifted and held in shifted position.

The carrier is yieldingly held in either working position by a latch in the form of

an angular lever 55 fulcrumed at the end of one arm to the machine frame and having its other arm cut to present a pair of faces 56 and 57 disposed in acute angular relation presented respectively to the faces of an angular projection 58 upon the carrier-bar. A spring 59 yieldingly retains the latch in working position. The object of the particular angular arrangement of the faces of the latch is to cause the carrier end to exert a glancing pressure thereon and thus secure slight frictional resistance which requires to be very light for the purpose.

The feed-pawl rocker frame 9 consists of a plate or thin flat bar cut to U-form with its legs 60 bent at right angles to its cross-bars and fulcrumed at about the middle to the ends 8 of the bracket 6. The upper ends of the arms are straddled by and have pivotally connected thereto a pair of split blocks 61, the forward ends of which are vertically perforated to afford journals for the inner ends of a pair of ribbon-drum actuating pawls 62 projecting through the arches of the frame in which their sliding oscillatory movements are accommodated. These blocks provide joints accommodating motion of the pawls in two directions, the motion in one direction being on the pivotal connection of the blocks to the legs 60, and the motion in the other direction being on the pivot of the pawl in the block. The outer ends of the pawls are guided in the supporting members before mentioned. This rocker-frame is actuated synchronously with each action of the writing mechanism by a link 65 connecting the same to the dog rocker bar 50. These pawl supporting members consist of angle-plates 70 connected by screws 71 through the slots 16 in the ends of the carrier 2 and threaded into the members, the outer edges of the ends establishing the proper tangential position of these members with relation to the ribbon spools and slots permitting proper angular adjustment in assembling the machine. The upper portions of these angle-plates have inclined slots 75 in which the free ends of the pawls lie with a tendency, due to gravitation, to remain at the lower ends of the slots and consequently at a point, with the members properly adjusted, at which they obtain most effective engagement with the ribbon spool ratchet wheels. The upper ends of these angle-plates carry the ribbon spool retaining pawls 80 which are comparatively wide and struck from a plate with lugs 81 bent at right angles and pivoted on a pin 82 mounted in lugs 83 struck up from the angle-plate and set diagonally to impart to the pawls a tendency, due also to gravitation, to lie in contact with the ratchet wheels. Upwardly extending bent back lugs 86 upon the pawls imparting to them the properties of latches and the operating ends of the

actuating pawl are bent back at 90° for the same purpose, thus enabling the ribbon spools to automatically displace these pawls if they should be in the way when the spools are set in place.

There has been considerable defective work caused by the loss of the friction devices for retarding the rotation of the ribbon spools and the consequent feeding of more ribbon than necessary to the ribbon guide. This is obviated by the particular construction of the friction devices each consisting of a resilient thin flat sheet metal bar 95 bowed as shown in Fig. 3 and having lugs 96 adapted to engage slots 97 in the floor of the ribbon-spool case 98 while a pair of diverging lugs 99 at each side of each of the lugs 96 bear on the floor and yieldingly sustain the bars 95 in frictional engagement with the spools. With this construction each friction device must be sprung to be set in place or removed and is self retaining when in position.

Operation: Each action of the writing mechanism as usual operates the dog-rocker bar 50, and consequently the rocker-frame 9, the pawls and the particular ribbon spool engaged; and the arms 51 with the fingers 52 are simultaneously operated. When the ribbon is almost all fed from one spool to the other and an enlargement upon the ribbon engages the particular ribbon guide 28 at that side of the machine, the slide 20 to which that ribbon-guide is connected is displaced and the dog 25 thereon engaged by one of the fingers 52, the effect being that the carrier 2 is swung on its pivot and the pawls 62 shifted from one spool to the other. It is to be noted that it is not necessary for the ribbon to move more than one ribbon guide the dog 25 in operative relation therewith and the intermediary parts, which constitute an individual mechanism offering minimum resistance to the ribbon. When the ribbon has not displaced either ribbon-guide and the operator inadvertently moves one of them when writing is not being done it will be returned to normal position by the spring 24 immediately the operator releases it, thus obviating the more frequent reuse of one part of the ribbon than another and in consequence securing uniform wear thereof.

What I claim is as follows:—

55. 1. The combination with a part movable in unison with each writing action of the machine, and ribbon feeding devices of means for reversing the action of the latter comprising a pair of members located at opposite sides of the printing point and acted upon by the ribbon when it nears the ends of its travel in either direction, independently operating individual mechanisms operatively connected to the respective members, such mechanism being normally stationary rela-

tively to the part first mentioned, and means actuated through the medium of either of the said mechanisms and in operative relation with the feed devices, for the purpose of reversing the same.

2. In a typewriting machine the combination with writing mechanism, a part movable in unison with each writing action of the machine, ribbon feeding and take-up spools, pawls for actuating the spools, means for vibrating the pawls, and a pair of movable ribbon guides located at opposite sides of the machine, of a movable member supporting the pawls with one pawl engaging one of the spools and the other pawl out of engagement with the other spool, relatively movable devices displaceably mounted upon the said member and adapted when in one position to be engaged by the first mentioned part to move the member and displace the pawls and when in another position to clear the said part, and independent operative connections between the respective devices and guides.

3. In a typewriting machine the combination with writing mechanism, a part movable in unison with each writing action of the machine, ribbon feeding and take-up spools, displaceable actuating pawls for engagement with the spools, means for vibrating the pawls, and a pair of movable ribbon guides located at opposite sides of the machine, of a pivoted member supporting the pawls with one pawl in engagement with one of the spools and the other pawl out of engagement with the other spool, and means operatively connected to the said ribbon guides and whereby the said first mentioned part operates the said pivoted member for the purpose of displacing the pawls and changing their operative relation to the spools.

4. In a typewriting machine the combination with ribbon feed and take-up spools, and means including pawls for actuating the said spools individually, of a pair of ribbon actuated devices, a horizontally rocking bar having devices at its ends guiding the pawls, means operatively connecting the ribbon actuated devices to the bar, and means operated by the writing mechanism for operating the said bar through the medium of the said ribbon actuated devices for the purpose of shifting one of the pawls into engagement with one of the spools and the other pawl out of engagement with the other spool.

5. In a typewriting machine the combination with ribbon feed and take-up spools, and means including pawls for actuating the said spools individually, of a pair of ribbon actuated devices, a horizontally rocking bar having devices at its ends guiding the pawls, independently operating mechanisms operatively connecting the respective ribbon actuated devices to the bar, and

- means operated by the writing mechanism for operating the said bar through the medium of the said ribbon actuated mechanisms for the purpose of shifting one of the pawls into engagement with one of the spools and the other pawl out of engagement with the other spool.
6. In a typewriting machine the combination with a part operated by the writing mechanism, ribbon spools, and means, including pawls, for actuating the spools individually, of a pair of ribbon actuated members, a horizontally rocking bar having devices at its ends for guiding the pawls, independently operating mechanisms carried by the bar at opposite sides of its pivot and adapted to in certain positions coact with the said first mentioned part in rocking the bar, means operatively connecting the respective members to the said mechanisms to shift the same.
7. In a typewriting machine the combination with a dog-rocker, ribbon spools, a pair of pawls for operating the spools, and means for vibrating the pawls, of a horizontally rocking bar having guiding devices at its ends in which the pawls are supported in operative relation with one or the other spool according to the position of the bar, a pair of relatively movable slides mounted upon the bar and each having a lateral dog, means yieldingly retaining the slides in normal position, a pair of arms upon the dog-rocker and constructed and disposed to engage either lateral dog when the slide bearing the latter is shifted from normal position, a pair of relatively displaceable ribbon guides, means operatively connecting the ribbon guides to the slides.
8. In a typewriting machine the combination with a dog-rocker, ribbon spools, a pair of pawls for operating the spools, and means for vibrating the pawls, of a horizontally rocking bar having guiding devices at its ends in which the pawls are supported in operative relation with one or the other spool according to the position of the bar, a pair of relatively movable slides mounted upon the bar and each having a standard and a lateral dog, means yieldingly retaining the slides in normal position, a pair of arms upon the dog-rocker and constructed and disposed to engage either lateral dog when the slide bearing the latter is shifted from normal position, a pair of relatively displaceable ribbon guides having arms with forked arms projecting in lines coincident with arcs described by the rocker-bar and engaging the standards.
9. In a typewriting machine the combination with a dog-rocker, ribbon spools, a pair of pawls for operating the spools, and means for vibrating the pawls, of a horizontally rocking bar having guiding devices at its ends in which the pawls are supported in operative relation with one or the other spool according to the position of the bar, a pair of relatively movable slides mounted upon the bar and each having a lateral dog, means yieldingly retaining the slides in normal position, a pair of arms upon the dog-rocker and constructed and disposed to engage either lateral dog when the slide bearing the latter is shifted from normal position, a pair of relatively displaceable ribbon guides, means for limiting the movement of the slides, a retractile helical spring connecting the slides together, a pair of arms upon the dog rocker and constructed and disposed to engage either lateral dog when the slide bearing the latter is shifted from normal position, a pair of relatively displaceable ribbon guides, means operatively connecting the ribbon guides to the slides.
10. In a typewriting machine the combination with ribbon feed and take-up spools, and means including pawls for actuating the said spools individually, of a pair of ribbon actuated devices, a horizontally rocking bar having devices at its ends guiding the pawls, means yieldingly retaining the bar in its different positions, means operatively connecting the ribbon actuated devices to the bar, and means operated by the writing mechanism for operating the said bar through the medium of the said ribbon actuated devices for the purpose of shifting the pawls and reversing the action of the feed devices.
11. In a typewriting machine the combination with a dog-rocker, ribbon spools, a pair of pawls for operating the spools, and means for vibrating the pawls, of a horizontally rocking bar having guiding devices at its ends in which the pawls are supported in operative relation with one or the other spool according to the position of the bar, means for yieldingly retaining the rocking bar in its different positions, a pair of relatively movable slides mounted upon the bar and each having a lateral dog, means yieldingly retaining the slides in normal position, a pair of arms upon the dog-rocker and constructed and disposed to engage either lateral dog when the slide bearing the latter is shifted from normal position, a pair of relatively displaceable ribbon guides, means operatively connecting the ribbon guides to the slides.
12. In a typewriting machine the combination with a dog-rocker, ribbon spools, a pair of pawls for operating the spools, and means for vibrating the pawls, of a horizontally rocking bar having guiding devices at its ends in which the pawls are supported in operative relation with one or the other spool according to the position of the bar, means for yieldingly retaining the rocking bar in its different positions consisting of an angular finger yieldingly mounted and having bearing faces in acute angular arrangement, a pair of relatively movable slides mounted upon the bar and each having a lateral dog, means yieldingly retaining the slides in normal position, a pair of arms upon the dog-rocker and constructed and disposed to en-

- gage either lateral dog when the slide bearing the latter is shifted from normal position, a pair of relatively displaceable ribbon guides, means operatively connecting the ribbon guides to the slides.
13. In a typewriting machine the combination with ribbon spools and pawls for actuating the same, of devices having inclined slots extending downwardly toward the spools and having the operating ends of the pawls resting therein.
14. In a typewriting machine the combination with ribbon spools and pawls for actuating the same, of diagonally pivoted retaining pawls for engagement with the spools.
15. In a typewriting machine the combination with ribbon feed and take-up spools, of a part operated by the writing mechanism, a pair of pawl guides adjacent and tangential to the spools and having inclined slots extending downwardly toward the spools, a pair of pawls guided in the said slots, means operatively connecting the pawls to the said part, and means for shifting the pawl guides for the purpose of moving one pawl into engagement with one spool and the other pawl out of engagement with the other spool.
16. In a typewriting machine the combination with ribbon feed and take-up spools, of a part operated by the writing mechanism, a vertically rocking member operatively connected to the said part, a pair of pawl guides adjacent and tangential to the spools and having inclined slots extending downwardly toward the spools, a pair of pawls operatively connected at one end to the said rocking member and guided at their opposite ends in the said slots, and means for shifting the pawl guides for the purpose of moving one pawl into engagement with one spool and the other pawl out of engagement with the other spool.
17. In a typewriting machine the combination with ribbon feed and take-up spools, of a part operated by the writing mechanism, a vertically rocking member operatively connected to the said part, a pair of pawl guides adjacent and tangential to the spools and having inclined slots extending downwardly toward the spools, a pair of pawls operatively connected at one end to the said rocking member and guided at their opposite ends in the said slots, a pair of spool retaining pawls diagonally pivoted to the guides and means for shifting the pawl guides for the purpose of moving one pawl into engagement with one spool and the other pawl out of engagement with the other spool.
18. In a typewriting machine the combination with a dog-rocker, ribbon spools, a pair of pawls for operating the spools, and means for vibrating the pawls, of a hor-
- izontally rocking bar carrying at its ends a pair of pawl guides adjacent and tangential to the spools and having inclined slots extending downwardly toward the spools in which the pawls are supported in operative relation with one or the other spool according to the position of the bar, a pair of relatively movable slides mounted upon the bar and each having a lateral dog, means yieldingly retaining the slides in normal position, a pair of arms upon the dog-rocker and constructed and disposed to engage either lateral dog when the slide bearing the latter is shifted from normal position, a pair of arms upon the dog-rocker and constructed and disposed to engage either lateral dog when the slide bearing the latter is shifted from normal position, a pair of relatively displaceable ribbon guides, means operatively connecting the ribbon guides to the slides.
19. In a typewriting machine the combination with a dog-rocker, ribbon spools, a pair of pawls for operating the spools, and means for vibrating the pawls, of a horizontally rocking bar carrying at its ends a pair of pawl guides adjacent and tangential to the spools and having inclined slots extending downwardly toward the spools in which the pawls are supported in operative relation with one or the other spool according to the position of the bar, a pair of spool retaining pawls diagonally pivoted to the guides, a pair of relatively movable slides mounted upon the bar and each having a lateral dog, means yieldingly retaining the slides in normal position, a pair of arms upon the dog-rocker and constructed and disposed to engage either lateral dog when the slide bearing the latter is shifted from normal position, a pair of relatively displaceable ribbon guides, means operatively connecting the ribbon guides to the slides.
20. In a typewriting machine the combination with the machine frame, a pair of ribbon-spools and a part operated by the writing mechanism, of means for actuating the spools comprising a vibratory frame, means pivoting the vibratory frame to the machine frame, means operatively connecting the said operated part to the said vibratory frame, a pair of rods with pawls formed at their outer ends for engagement with the spools, means locating the pawls relatively to the spools and joints accommodating motion in two directions for fastening the inner ends of the said rods to the vibratory frame.
21. In a typewriting machine the combination with a main frame, a quadrantal frame mounted thereon and having radial frame bars with arches, and a dog-rocker bar 50 mounted in the main frame, of ribbon spools rotatably mounted upon the main frame; bracket 6 secured to the quadrantal frame and having arm 4; bar 2 pivoted to arm 4 and having angular ends 10; guides for the bar consisting of plates 12 and 13.

- secured across the said arches; angular pawl-supporting and guiding plates 70 secured to the ends of the bar 2 and having inclined slots 75; pawls consisting of plates 80 with lugs 86 fulcrumed diagonally to the plates 70; slides 20 upon the bar 2 and having oppositely facing hooks 23, standards 26 and offset dogs 25; means slidably connecting the slides to the bar; a retractile helical spring 24 yieldingly connecting the hooks together; ribbon guides 28 fulcrumed to the quadrantal frame and having forked arms 27 engaging the standards 26; arms 51 mounted rigidly upon the dog-rocker and having spaced fingers 52 for engagement with dogs 25 when the slides are shifted and provided 45 with spaced fingers 52; rocker-frame 9 with legs 60 fulcrumed between their ends to the bent ends 8; link 65 connecting the lower end of the rocker-frame to the dog-rocker; blocks 61 pivoted to the upper ends of the 50 legs 60; pawls 62 journaled in the blocks and projecting through the arches and through and resting in slots 75 for engagement with one or the other of the spools.
23. In a typewriter the combination with 55 the ribbon-spool-case, the spool therein and the pin upon which the spool rotates, of a unitary friction device between the spool and floor of the case and having integral means whereby it is detachably connected to 60 the case.
24. In a typewriter the combination with the ribbon-spool-case having slots in its floor, the spool therein and the pin upon which the spool rotates, of a friction device 65 for retarding the rotation of the spool consisting of a bowed resilient bar with lugs projected from its ends and engaging in slots in the floor and each end of the bar having a pair of diverging lugs at each side 70 of the projected lugs and bearing upon the floor.
- In testimony whereof, I have signed my name to this specification in the presence of two witnesses.
- GEORGE WILLIAM DAVIS.
